GRIP HANDLE OR SIMILAR ARTICLE

Clarence S. Burtchaell, Ross, Calif.

Application May 1, 1956, Serial No. 41,290

Term of patent 7 years

(Cl. D87—5)

Fig. 1 is a bottom perspective view of a grip handle or similar article, showing my new design;

Fig. 2 is a side elevational view thereof;

Fig. 3 is an end elevational view thereof, the opposite end having the same appearance; and

Fig. 4 is a top plan view thereof.

I claim:

The ornamental design for a grip handle or similar article, as shown and described.
